ELECTRIC CALCULATING MACHINE

René Edmond Boutet, Paris, France

Application December 27, 1934, Serial No. 759,387
In France February 14, 1934

9 Claims. (Cl. 235—92)

The present invention relates to an electric calculating machine and more particularly a machine for multiplying including a certain number of electric circuits the connections of which are made under conditions such that after the multiplier and the multiplicand have been entered in storage indicators and a distributor has been set in operation which closes contacts in the order required for the successive exploration of all the figures of the multiplier and the multiplicand storage indicators, the result is automatically stored in a storage indicator without any other member being in motion than the distributor and the switches.

Other characteristics and peculiarities of the invention will become apparent from the ensuing description taken in conjunction with the accompanying drawings in which:

Fig. 1a and 1b show a diagram of the whole device according to the invention.

Figs. 2a and 2b show a diagram of the multiplier circuits.

Fig. 3 shows a diagram of the adding circuits for the tens of the preceding product and the units of the new product.

Figs. 4a and 4b show a diagram of the adding circuits of the successive results and of the storage indicators for such results.

Figs. 5 to 8 illustrate the current distributors.

Fig. 9 is a side elevation of one of the drums forming the switches in the various circuits of the device.

Fig. 10 is a cross-section along the line X—X of Fig. 9.

Fig. 11 is an end elevation of the device of Fig. 9.

Fig. 12 is a view of a detail of the device of Fig. 9.

Fig. 13 is a plan view of one of the registers.

Fig. 14 is a corresponding elevation of the device of Fig. 13 with the front row of pins partly broken away to show the second row.

Fig. 15 is a partial end view of same.

The device according to the invention essentially comprises: a multiplicand storage indicator A, a multiplier storage indicator B, a multiplicand distributor C, a multiplier distributor D, a group of multiplying circuits E, a storage indicator F, for the tens of each product, a group of circuits G for adding the tens of the preceding product and the units of the new product, a register H for transferring these additions, a group of circuits K for adding the final results having a transfer-storage indicator P, a double storage indicator L—M for the results, a certain number

of associated devices connecting up the aforesaid members under the required conditions. Each of the aforesaid members will now be successively described.

1. *Multiplicand storage indicator*

This storage indicator could be constituted by a simple keyboard having a certain number of columns of ten keys, each of which would close a contact when it is depressed by hand or otherwise. However, in the example illustrated, this storage indicator is constructed so that it can be automatically controlled by any suitable associated machine e. g. the typewriter described in U. S. Patent No. 1,998,355. It comprises a certain number (3 in the example illustrated in Fig. 1a) of rows of pins: gu^0 gu^1 gu^2 gd^0 gd^1 gd^2 .

All the pins of the same denominational row, that is to say, those which correspond to the same denomination (for example all the pins gu^0 , gu^1 , gu^2 or gd^0 , gd^1 . . . or gc^0 , gc^1 . . .) are engaged in a link 10^u , 10^d , 10^c (Fig. 13) actuated by an electromagnet 11^u , 11^d , 11^c . To each of the columns of pins there corresponds moreover an actuating link 12^0 , 12^1 . . . 12^9 , controlled by an electromagnet 13^0 , 13^1 . . . 13^9 . As will be seen from Fig. 14 the pins are normally inclined and in this position, escape the action of the links 12 . On the contrary, when, by the action of the corresponding link 10 , all the pins of the same digital row have been brought into the vertical position (as the pins gd^5 , gd^6 , in Fig. 13) and if, the link 12 , corresponding to a certain column, is then depressed, it acts on the pin, then in the vertical position, and brings it into the depressed position. In other words, the electromagnets 11 select the denomination and the electromagnets 13 select the figure to be stored. It is these two groups of electromagnets which are controlled by the auxiliary machine.

Each pin of the same denominational row, made of conducting material, receives current from a lower bar 14^u , 14^d , 14^c (Fig. 14) and carries a contact 15 which, when the pin is depressed, comes into contact with a conducting bar 16 . . ., common to all the pins of the same digital row. Thus, when a pin is depressed, it establishes an electrical connection between a current lead in (bar 14) and a current lead out (bar 16). The various bars 14 are connected to the conductors 17^u , 17^d , 17^c (Fig. 1a) leading from the distributor C , whereas the bars 16 are connected to the wires 18^0 , 18^1 , 18^2 . . ., running towards the multiplying circuits E . Each pin gu , gd . . . is subjected to the action of a spring 19 which holds it in the

depressed position when it has been brought there. A disconnecting device shown in dotted lines in the form of a plate 9 raised at the right moment by electromagnets 8, restores simultaneously all the depressed pins to their normal position.

2. Multiplier storage indicator B

It is strictly in conformity with the multiplicand storage indicator and need not be described.

3. Multiplicand distributor C and multiplier distributor D

They are constituted by the device illustrated in Figs. 5 to 8. As for the storage indicators, it has been assumed in the drawings that the capacity of the machine was limited to three figures for the multiplicand and three figures for the multiplier, but it is obvious that it could be of any capacity.

On the shaft 20 of an electric motor 20^a, are mounted seven distribution cams 21^a 21^b 21^c . . . set in staggered relation, as can be seen in Fig. 8, and capable of successively closing the contacts 22^a 22^b 22^c . . . corresponding to the denominations of the multiplicand storage indicator and of the result. On the shaft 20 is also mounted a wheel 23 provided with a slot 24. On the periphery of said wheel bears a lever 25, the opposite end 26 of which is opposite an electromagnet 27, whereas its nose 28 is capable of closing a switch 29 interposed in the circuit of the motor 20^a. With this arrangement, each time the lever 25 is rocked by acting on its end 26, by means of the electromagnet 27, the contact 29 is closed; the motor 20^a is set in motion and the lever 25—26 is then held in its new position by the edge of the wheel 23. When this wheel is rotated one revolution, if the action on the end 26 has ceased, the motor stops, and the lever 25 falls back into the slot 24.

On the shaft 20 is also mounted a pinion 30 engaging with a pinion 31 of larger diameter, fast on a shaft 32 carrying cams 33^a 33^b 33^c 33^m adapted to close the contacts 34^a 34^b 34^c 34^m corresponding to the denominations of the multiplier storage indicator and another cam 35, 36, the function of which is to hold closed during one rotation of the shaft 32 a switch 36 closing the circuit of the electromagnet 27, so that the motor only stops after one complete rotation of said shaft 32. The ratio between the speeds of the axes 20 and 32 is such that when the shaft 20 rotates one revolution, only one of the cams 33 acts.

4. Group of multiplying circuits E

This group E is illustrated in detail in Figs. 2a and 2b. The wires 18¹ 18² . . . (Fig. 2a) come from the multiplicand storage indicator A. Each of them is connected to an electromagnet 40 adapted to close a contact 41 supplying three conductors simultaneously. Three groups of conductors are thus obtained: a group 42, a group 43 and a group 44.

With the group 42, the function of which is to indicate the figure of the units of each partial product, cooperates a group of circuits 45. These two groups of circuits can be connected by any one of the nine sets of conductors 46¹ . . . 46⁹, in each of which is interposed a switch 47¹ . . . 47⁹ which is closed when the corresponding electromagnet 48¹ . . . 48⁹ (see Figs. 1a and 1b) is closed, which occurs when the corresponding figure 1, 2 . . . is stored in the multiplier storage indicator B, that is to say when it is desired to multiply by

that figure. The sets 46 connect the wires of the group 42 to the wires of the group 45 in such a manner that each wire of the group 42 is connected by a definite set to the wire of the group 45 corresponding to the units figure of the product of the figure to which the wire 42 in question corresponds, by the figure to which the set 46 corresponds. For example, the wire 42⁶ can be connected, by the set 46³, to the wire 45⁸, because (8) is the units figure in the product of (6) by (3).

The group of wires 43, the function of which is to indicate the tens figure of each partial product, cooperates in a similar manner with a group 49 to which it can be connected by one of the sets 50, having a switch 51, closed at the same time as the corresponding switch 47. The connection made by the sets 50 is such that for example the wire 43⁶ can be connected, by the set 50³, to the wire 49¹, because (1) is the tens figure in the product of (6) by (3).

Finally the group 44, the function of which is to indicate the smallest figure which must be added to the units figure of the partial product to obtain a transfer, cooperates with a group 52¹ 52² . . . 52⁸, to which it is connected by the sets 53¹ . . . 53⁸, having a switch 54¹ . . . 54⁸ closed at the same time as the switches 47 and 51. The connection made by said sets 53 is such that for example the wire 44⁶ is connected, by the set 53³, to the wire 52², because the units figure (8) of the product of (6) by (3), gives a transfer when it is added to the figure (2) or to a higher figure. It will be seen hereinafter how this transfer indication is used.

As can be seen from the above explanations, the three switches 47, 51, and 54, corresponding to the same multiplier figure for example, the switches 47³, 51³, and 54³, are closed simultaneously when the electromagnet 48³ is energized. All these various switches can then be advantageously constructed in the manner illustrated in Figs. 9 to 12. In this embodiment the nine contacts of the switch 47 considered, 47³ for example, are constituted by nine pairs of blades 45 55. Each of these pairs of blades cooperates (Figs. 10 and 12) with two plates 56 and 57 which are respectively made of insulating material and conducting material. In the same manner the nine contacts of the corresponding switch 51³ are constituted by nine pairs of blades 58 and the nine contacts of the switch 54³, by nine pairs of blades 59, only two of which are shown in Fig. 9, it being understood that the seven others are mounted in sequence in an identical manner.

The insulating plates 56 and the conducting plates 57 are threaded in sequence on a central axis 60 and two parallel rods 61 mounted between two discs 62 which can be angularly displaced by an electromagnet 48 which, in this case, is the electromagnet 48³ (Fig. 1a). When this electromagnet is not energized, a spring 63 holds the discs 62 and consequently the plates 56 and 57 in the position illustrated in Figs. 9 and 10, in which each pair of blades is insulated by the corresponding plate 56. This is the open position of the switches 47³ 51³ and 54³. When, on the contrary, the electromagnet 48³ is energized, the group of discs 62 and of plates 56 and 57 is angularly displaced, and the plates 57 electrically connect the blades of each pair. The three switches considered are then in the closed position. There is of course a similar connecting device for each group of three switches corresponding to the nine first figures.

5. *Storage indicator F for the tens in each partial product*

This storage indicator F illustrated at the bottom and at the right of Fig. 1 is similar to the storage indicators A and B and will not be described. The wires 49 (see Fig. 2b) each control an electromagnet 64 selecting the figure, whereas the electromagnets 65^u 65^d 65^c select the denomination. When a pin of said storage indicator is depressed, it establishes an electrical connection between one of the current lead in wires 66^u 66^d 66^c and one of the lead out wires 67¹ 67² ... 67⁹.

6. *Group of circuits G adding the units to the tens of the preceding partial product*

These wires 67 lead, as shown (Figs. 1b and 3) to the adding mechanism G which is formed by the group of wires 45 coming from the multiplier circuit of Fig. 2, and a group 68, connected to the group 45 by sets 69, the switches 70 of which are controlled by the electromagnets 71 connected to the wires 67. The sets 69 make a connection such that for example the wire 45⁴ is connected, by the set 69³, to the wire 68⁷, because the sum of (4) and of (3) is (7). The group of transfer circuits 52 (Figs. 2b and 3) cooperates with these adding circuits to render operative the possible transfers. For this purpose the wires 52 can be connected to a transfer conductor 72 by sets 73, the switches 74 of which are closed at the same time as the corresponding switches 70. The switch 70 of each set and the corresponding switch 74 are constituted by means of a contactor similar to the one illustrated in Fig. 9.

The sets 73 make a connection such that if it is assumed for example that the unit figure arriving by the group 45 is the figure (6), it will be seen on looking at Fig. 2, that it is the wire 52⁴ which receives current, since it is from the figure (4) onwards that (6) gives a transfer. Now the said wire 52⁴ can be connected to the transfer wire 72 by the set 73⁴ and the following sets, so that the wire 72 will receive current if it is (4) or a higher figure which arrives by the group 67. It is obvious, however, that this transfer cannot be introduced immediately; it is registered by the device H and it is during the ensuing operation that it will be added.

For this purpose the wire 72 is connected to an electromagnet 75 adapted to close a switch 76 which, when closed, completes a circuit to all the electromagnets 77^d, 77^e ... one or the other of these electromagnets being energized, according to whether at that instant the distributor 55 closes one or the other of the switches 22^d, 22^e ... The electromagnet 77 which is thus energized then closes one of the switches 78^e, 78^m ... which when the following product is being calculated, causes the energization of the 60 electromagnet 79¹ instead of the electromagnet 79⁰ which is energized when there is no transfer. Said two electromagnets 79⁰ and 79¹ act on two connection shifters 80⁰ and 80¹, which connect the group of wires 68 to a group 81; the shifter 65 80⁰ makes a straight connection, the wire 68¹ being connected to the wire 81¹ and so forth, whereas the shifter 80¹ makes this connection with an increase of one unit, the wire 68¹ being connected to the wire 81² and so forth. An electromagnet 82 energized when the distributor contacts with the stud 22^e, enables the switches 78 to be brought back to their normal position of non-transfer (position illustrated in Fig. 3). The electromagnets 77 are supplied through the 70 instrumentality of switches 114^u, 114^d closed by

the electromagnets 113^u, 113^d ... when the corresponding switches 22 are closed.

7. *Group of adding circuits K and double storage indicator LM*

This unit is illustrated in Figs. 4a and 4b. The group 81 which leads from the shifters 80 (Fig. 3) cooperated with a group 83 through which it can be connected by sets 84, the switches 85 of which are controlled by the electromagnets 106. The sets 84 make a connection such that, for example, the wire 81⁴ is connected, by the set 84³, to the wire 83⁷, since the sum of (4) and (3) is (7). The group 83 is connected to a group 87 through the instrumentality of either of the two shifters 88⁰, 88¹ the first acting when there is no transfer, the second acting when there is one. The wires of the group 87 are connected to electromagnets 89 which select the figures in a double storage indicator, the two portions L 20 and M of which are similar to the storage indicator illustrated in Figs. 13 to 15. In said storage indicators the denominations are selected by electromagnets 90^u, 90^d ... and 91^u, 91^d ... The current is supplied to the columns of the storage indicator M by contacts 92^u, 92^d ... and to those of the storage indicator L by contacts 93^u, 93^d ... Said two storage indicators operate alternately, that is to say that when one of the two stores a partial product, by means of the electromagnets 89, the other sends the figure of the preceding product into the group of adding circuits, 81, 83, through the instrumentality of the contacts 94 and the electromagnets 86. Said two storage indicators change function alternately for each figure of the multiplier.

In order to obtain this alternation, the electromagnets 90 of the storage indicator M and the contacts 93 of the storage indicator L are connected simultaneously to the current lead in by 40 the conductors 98 and the switch 96 closed by the electromagnet 97^{dm}, when the distributor of the multiplier is on the switches corresponding to the tens, or to the thousands, whereas the electromagnets 91 of the storage indicator L and 45 the contacts 92 of the storage indicator M are connected simultaneously to the current lead in by the conductors 95 and the switch 99, which is closed alternately with the switch 96, by an electromagnet 100^{uc}, energized when the distributor 50 is on the units or hundreds.

In the adding mechanism 81—83 (Figs. 4a and 4b), the transfers are made by means of a group 101 connected by means of the switch 102⁰, or the switch 102¹, which sets back by one unit, to 55 a group 103 the conductors of which include contacts 104, closed when the corresponding electromagnet 89 is itself energized. Said group 101 can be connected to a wire 105, by sets 106, the switches 107 of which are closed at the same 60 time as the switches 85. The connection made by the sets 106 is such that the wire will receive current when, assuming that the switch 102⁰ is closed, and the switch 102¹ open, the sum of the figure to which the closed switch 107 corresponds and of the figure to which the contact 104, which is also closed, corresponds, is greater than 9, that is to say when a transfer is to be made in the following operation. If it is then assumed that the distributor is on "units", the 70 electromagnet 108^u is energized and actuates the double-throw switch 109^u which during the following operation will cause the electromagnet 110¹ to be energized, said electromagnet then closing the shifter switches 102¹ and 88¹, instead 75

of the electromagnet 110⁰ which closes the switches 102⁰ and 88⁰ when there is no transfer.

The shifter 88¹ will then increase by one unit the result transmitted by the group 83, which is the purpose required. The object of the shifter 102¹ is to control the registration of a fresh transfer when, owing to the addition of a transfer, such fresh transfer becomes necessary.

In the above description, a certain number of parts have not been described: they will be described in the description of the operation which will now be given, assuming that it is required to multiply (86) by (67).

(86) is recorded in the storage indicator A and (67) in the storage indicator B, and the distributor is set in operation. The contact 34^u of the multiplier closes and will remain closed during one revolution of the shaft 20; as in the units column of the storage indicator B it is the figure (7) which is stored, the electromagnet 48⁷ will be energized and will close the switches 47⁷, 57⁷ and 54⁷ (Fig. 2a and Fig. 2b).

I. Multiplication of the units figure (6) of the multiplicand by the units figure (7) of the multiplier

During the rotation of the shaft 20 of the distributor the first contact which is closed is the contact 22^u. The current then flows through the shifter 111^u, closed by the electromagnet 112^u, and which produces no shift, to the electromagnet 113^u which closes the switch 114^u, so that the wire 17^u receives current (Fig. 1a). As in the units column of the distributor A, it is the figure (6) which is stored, it is the wire 18⁶ which receives current, and causes the closing of the contact 41⁶ (Fig. 2a) which makes three circuits:

1. The wire 42⁶ being connected by the set 46⁷, then in service, to the wire 45², it is the latter which receives current, (2) being the units figure of the first partial product of (6) by (7). As nothing is yet stored in the tens storage indicator F, the wire 45² is connected by the set 69⁰ (Fig. 3) to the wire 68², itself connected to the wire 81² which is connected, by the set 84⁰ (Fig. 4b) then closed, since nothing is stored in the units column of the storage indicator M, and by the switch 88⁰, to the wire 87². The electromagnet 89² is energized, and as, at this moment, it is the switch 99 which is closed, the electromagnet 91^u is energized and the figure (2) is stored in the units column of the lefthand storage indicator L, since owing to the closing of the switch 99 which will remain closed during the whole multiplication by the units figure of the multiplier, said storage indicator L will store the results transmitted by the wires 87, whereas the storage indicator M controls the electromagnets 86 through the contacts 94.

2. The wire 43⁶ (Fig. 2a) is connected, by the set 50⁷, to the wire 49⁴, (4) being the tens figure of the same partial product of (6) by (7). The electromagnet 64⁴ is then energized, and as the electromagnet 65^u is energized at the same time, the figure 4 is stored provisionally in the units row of the tens storage indicator F. It will be subsequently totalized with the units figure of the ensuing partial product.

3. The wire 44⁶ (Fig. 2a) is connected, by the set 53⁷, to the wire 52⁸, for showing the transfers; in view of the fact, however, that for this first product there is no addition to be made, said wire at this time does not come into operation.

Thus, at this time the units figure (2) is stored

in the storage indicator L, and the tens figure (4) in the storage indicator F.

II. Multiplication of the second figure (8) of the multiplicand by the first figure (7) of the multiplier

The electromagnet 48⁷ remains energized, but it is the contact 22^d which closes, causing current to be supplied to the wire 17^d (Fig. 1a). As it is the figure (8) which is stored in the tens column of the register A, it is the wire 18⁸ which receives current and causes the closing of the contact 41⁸ (Fig. 2a). The three wires 42⁸, 43⁸ and 44⁸ simultaneously receive current.

The wire 42⁸ is connected by the set 46⁷, then in service, to the wire 45⁶ of the adding device G. The units figure (6) of the second partial product must now be totalized with the tens figure (4) of the preceding product; this is obtained in the following manner: the wire 66^d receiving current through the closed switch 114^d, and the pin (4) of the units row of the storage indicator F being depressed, the wire 67^d receives current; the electromagnet 71^d is energized and closes the switches 70^d and 74^d (Fig. 3). The wire 45⁶ which receives the current, is then connected, by the set 69⁴, to the wire 68⁰, (0) being the units figure of the sum of (6) and (4).

The transfer for the ensuing product is shown due to the fact that the wire 44⁸ (Fig. 2a) is connected, by the set 54⁷, to the wire 52⁴ (Figs. 2b and 3), which is connected, by the set 73⁴, to the wire 72. The electromagnet 75 is then energized, the switch 76 closed and the electromagnet 77^d energized. The double-throw switch 78^c is then brought into the position in which, during the storing of the hundreds, it will control the closing of the shifter 80¹, as will be seen hereinafter.

As for the first partial product, the storage indicator F stores in the tens row, by means of the wire 42⁸ and the wire 49⁶, the figure (5), which is the tens figure of the second partial product of (8) by (7).

It has therefore been seen that as (0) is the units figure obtained when the units figure (6) of said second product is added to the tens figure of the first product, it is the wire 68⁰ (Fig. 3) which received current. As it is always the switch 80⁰ which is in service, it is the wire 81⁰ which receives current. Said wire 81⁰ is connected by the set 84⁰ and switch 88⁰ to the wire 87⁰, since it is the electromagnet 86⁰ which is energized, owing to the fact that nothing is stored in the tens column of the storage indicator M. The electromagnet 89⁰ is then energized and the figure (0) is stored in the tens column of the storage indicator L, since it is still the switch 99 which is closed, the distributor of the multiplier being still on the units.

At this moment therefore the units figure (2) is in the units column of the storage indicator L, the tens figure (0) in the tens column of said storage indicator L, the figure (5) in the tens row of the storage indicator F, and a transfer pending on the hundreds owing to the fact that the double-throw switch 78^c is in the transfer position.

III. Storing of the hundreds figure of the first partial product

The electromagnet 48⁷ remains energized, but it is the contact 22^c which closes. As nothing is recorded in the hundreds column of the storage indicator A, it is the wire 42⁰ which receives the current and transmits it to the wire 45⁰ (Fig. 3).

With the wire 66^c receiving current and the pin 5 being depressed in the corresponding row of the storage indicator F, the wire 67^c receives current, causing the energization of the electromagnet 71^c.

- 5 The wire 45^c is then connected to the wire 68^c. But as the double-throw switch 78^c had been brought into the transfer position, the electromagnet 79^c is energized, and the shifter 80^c is in service, so that the wire 68^c is connected to the wire 81^c. As nothing is yet stored in the hundreds column of the storage indicator M, it is the electromagnet 86^c which is energized (Fig. 4), so that the wire 81^c is connected by the set 84^c, to the wire 83^c, which is itself connected, by the switch 15 88^c, to the wire 87^c, which causes the energization of the electromagnet 89^c and the storing of the figure (6) in the hundreds column of the storage indicator L, since at this time the electromagnet 91^c is energized.
- 20 Thus, after the multiplication of the two figures of the multiplicand by the first figure of the multiplier, the storage indicator L has stored the figure (2) in the units column, the figure (0) in the tens column and the figure (6) in the hundreds column, which makes the number (602), which is actually the product of (86) by (7).

As the distributor continues to rotate, the various contacts 22^m, 22^{dm} . . . close without giving any result, since there is no figure stored in 30 the corresponding columns of the storage indicator A, and there is no transfer pending in the device.

Then the contact 22^c closes, causing the electromagnets 82 and 116 to be energized, and the corresponding double-throw transfer switches to be restored to the normal position. Simultaneously the contact 22^c causes the energization of an electromagnet 130^a, (Fig. 1b), which acts on a disconnecting plate bringing back in the normal position all the pins of the tens storage indicator F, previously depressed, said disconnecting plate being similar to the plate 9 illustrated in Fig. 14. On the other hand, the closing of the contact 22^c controls the energization of the electromagnet 130 (or 131) which brings back to their normal 45 position all the pins depressed in that storage indicator L or M which has just acted as a control member of the electromagnet 86.

In the drawings it has been assumed that the multiplicand could only have three figures at the 50 most (see storage indicator A). Under these circumstances, only the contacts 22^c, 22^d and 22^e can be connected to said storage indicator A, through the switches 114. On the other hand, the contacts 22^m, 22^{dm}, and 22^{cm} only serve for storing 55 the results which can of course have six figures; said contacts do not serve for the multiplicand and it is for this reason that instead of being adapted to be connected to the storage indicator A, they are simply connected to the wire 42^c. But it is obvious that if the storage indicator A had more than three denominations, said contacts 22^m, 22^{dm} and 22^{cm} would be, as are the others, connected to said storage indicator.

65 IV. Multiplication of the first figure (6) of the multiplicand by the second figure (6) of the multiplier

The shaft 20 of the distributor having thus made a complete revolution, the contact 34^c opens, whereas the cam 33^d closes the contact 34^d, causing the energization of the electromagnet 48^c, since (6) is stored in the tens column of the storage indicator B, as the shaft 20 continues to rotate, it closes again successively the contacts 75 22^c 22^d . . .

But in this case, it is the electromagnet 112^d which is energized, putting into service the shifter 111^d, by means of which the necessary shifting of one denomination is obtained, the contact 22^c being connected, for example, to the wire 42^c, whereas the contact 22^d is connected to the wire 17^c of the storage indicator of the multiplicand A, and so forth.

At the closing of the contact 22^c, it is therefore the wire 42^c which receives current, said wire being connected through the wire 45^c and switch 70^c which is now closed, to the wire 68^c, which is itself connected to the wire 81^c. Owing to the fact that it is now the electromagnet 97^{dm} which is energized, it is the switch 96 which is closed, so that the storage indicator L which, during the preceding operations, acted as a store, will now act as a transmitter of the figures to the adding device K, whereas the storage indicator M which previously acted as a transmitter will now act as a storage indicator. It has been previously seen that in the units column of the register L, it was the figure (2) which was entered. When the contact 22^c is closed, the contact 93^c therefore receives current which is transmitted by the 20 corresponding pin 2 to the contact 94^c, thus causing the energization of the electromagnet 86^c and consequently the closing of the switch 85^c. The wire 81^c which, as has been seen, receives current, is therefore connected by the set 84^c to the 30 wire 83^c, which is itself connected, through the switch 88^c then closed, to the wire 87^c which causes the energization of the electromagnet 89^c and the entering of the figure (2) in question in the units column of the register M.

In fact said figure (2) has only passed from the column of the storage indicator L into the units column of the storage indicator M. The switch 22^d then closes, the wire 17^c is connected, (6) being entered in the units column of the 40 storage indicator A) to the wire 18^c. The wire 42^c is then connected by the set 46^c to the wire 45^c (Fig. 3). As nothing is entered in the storage indicator F, the electromagnet 71^c is energized, and the wire 45^c is then connected to the 45 wire 68^c, then to the wire 81^c. Now at this time the electromagnet 86^c is energized, since in the tens column (then in service) of the storage indicator L, it is the figure (0) which is entered. The wire 81^c is then connected by the set 84^c 50 and the switch 88^c to the wire 87^c. The electromagnet 89^c is energized, and causes the entering of the figure (6) in the tens column of the storage indicator M.

On the other hand, and simultaneously with 55 the wire 42^c, the wire 43^c has received current and has caused the tens figure (3) to be entered in the tens column of the storage indicator F through the wire 50^c, switch 53^c (now closed since the multiplier figure is (6), wire 49^c, and electromagnet 64^c. The wire 44^c has also received current, but has not produced any effect as it was the electromagnet 71^c which was energized, so that no transfer was possible.

65 V. Multiplication of the second figure (8) of the multiplicand by the second figure (6) of the multiplier

The contact 22^c closing in its turn, the wire 70 17^c receives current, transmits it to the wire 18^c, which itself transmits it to the wires 42^c, 43^c and 44^c. The wire 42^c is connected, by the set 46^c, to the wire 45^c (Fig. 2b), itself connected (Fig. 3), by the set 69^c, (the figure (3) having been 75 previously entered in the storage indicator F)

to the wire 68¹ which, by means of the switch 80⁰, is connected to the wire 81¹. Said wire 81¹ is itself connected, by the set 84⁶, (since it is the figure (6) which is entered in the hundreds 5 column of the storage indicator L) to the wire 83⁷, itself connected, by the switch 88⁰, to the wire 81⁷, which causes the energization of the electromagnet 89⁷ and the entering of the figure (7) in the hundreds column of the storage indicator M. Simultaneously with the wire 68¹, the wire 72 has received current, since the addition of (8) and (3) gives (1) as the unit, and (1) as the tens; owing to this fact the electromagnet 77^c is energized, and the double-throw switch 15 78^m brought to the transfer position.

Owing to the fact that the wire 43⁸ (Fig. 2a) has also received current, the figure (4) representing the tens figure of the partial product of (8) by (6) has been entered in the hundreds 20 row of the storage indicator F.

As the distributor continues to rotate, the contact 22^m closes. As nothing is entered in the hundreds column of the storage indicator A, it is the wire 18⁰ which receives the current, and 25 transmits it to the wire 42⁰, which is itself connected to the wire 45⁰, which is connected, by the set 69⁴, (since the figure (4) is entered in the storage indicator F) to the wire 68⁴ connected, by the switch 80¹, (since the double-throw switch 30 78^m is in the transfer position) to the wire 81⁵.

As nothing is entered in the thousands column of the storage indicator L, said wire 81⁵ is connected, by the set 84⁰, to the wire 83⁵, itself connected, by the switch 88⁰, to the wire 35 87⁵, which energizes the electromagnet 89⁵ and causes the figure (5) to be entered in the thousands column of the storage indicator M. Said storage indicator will therefore show finally the number 5762, which is actually the product of 40 86×67.

The distributor continues to rotate until the shaft 20 has effected a complete revolution. At this instant its motor 20^a will stop, and a fresh operation can be carried out.

45 In the example illustrated, the addition of the figure represented by the wire 81 receiving current (Fig. 4a), and of the figure represented by the electromagnet 86, has never given a transfer, so that the switch 88⁰ has always remained in 50 service. It will readily be understood that when such addition gives a transfer, owing to the closing of the switch 104 corresponding to the electromagnet 89 energized, and owing to the closing of the switch 107 corresponding to the electromagnet 86 energized, the wire 105 will receive current and cause the placing in the transfer position of that double-throw switch 109, which has to operate when the ensuing operation takes place, during which it is then the shifter 88¹ 55 which will be operative, and increase by one unit the figure represented by the wire 83 then receiving current.

The showing is for a machine suitable for having three orders in each of a multiplier and 60 multiplicand whereas it is not intended to confine the invention to such numbers or orders. Certain of the elements vary with the numbers or orders as follows:—

65 "A" and "B" may have any desired number 70 of orders.

Distributor "C", and also "L" and "M" must have as many orders as the sum of orders in "A" and "B"; thus if "A" and "B" each have three orders, "C", "L" and "M" must have six 75 orders.

"D" must have one more order than "B".

There must be as many switches 111 and coils 112 as orders "B". There must be one more switch 114 and coil 113 as orders "A".

"F" must have as many orders as "A".

There must be as many switches 132 and coils 133 as orders in "C". There is one less number of coils 77 and switches 78 than there are orders in "A".

There is one less number of coils 108 and 10 switches 109 than there are orders in the distributor "C". Those switches from 114^c to the next to highest order have five contacts, the highest order has three contacts.

It is moreover obvious that the invention has 15 only been described herein in a purely explanatory but by no means limitative manner, and that various modifications of detail could be made therein within the scope of the appended 20 claims.

I claim:

1. A calculating machine comprising a multiplicand storage indicator, a multiplier storage indicator, a product storage indicator and a tens storage indicator, electric contact means selectively operable by said multiplicand and multiplier storage indicators, a distributor adapted to send an electric current successively into each denomination of the multiplier storage indicator, and, for each of said denominations of the multiplier storage indicator, into each denomination of the multiplicand storage indicator, a group of multiplying circuits adapted to be connected to said multiplicand and multiplier storage indicators and giving the units figure and the tens figure of each partial product, electromechanical means for transferring said units figure to said product storage indicator, electromechanical means for temporarily storing said tens figure in said tens storage indicator, electromechanical tens adding means for adding to the units figure of each partial product the tens figure temporarily registered during the formation of the preceding product, and electromechanical means for adding to each total figure transmitted by said tens adding means the preceding figure stored by the product storage indicator in the same denomination.

2. A calculating machine comprising a multiplicand storage indicator, a multiplier storage indicator, a product storage indicator and a tens storage indicator, electromechanical contact means selectively operable by said multiplicand and multiplier storage indicators, a distributor adapted to send an electric current successively into each denomination of the multiplier storage indicator, and, for each of said denominations of the multiplier storage indicator, into each denomination of the multiplicand storage indicator, a group of multiplying circuits adapted to be connected to said multiplicand and multiplier storage indicators, and including a series of nine electromagnets, each of which is energized when the digit to which it corresponds is entered in the multiplier storage indicator and the distributor connects the corresponding multiplier order, a group of ten multiplicand conductors, each of which is adapted to receive current when the figure to which it corresponds is entered in the multiplicand storage indicator and the distributor connects the corresponding multiplicand order, a second group of ten multiplicand conductors each of which is adapted to be connected by a switch to the corresponding conductor of the first mentioned multiplicand group, electro- 40

magnets for controlling said switches, and a series of nine sets of conductors, (one set for each of the nine digits) each set provided with a switch which is closed when the corresponding electromagnet is energized, and which thereby connects that conductor, of said second group of ten conductors, which receives current, to a conductor forming part of a group of conductors, said latter conductor corresponding to the figure representing the units of the partial product, electromechanical means for obtaining the tens figure of each partial product, electromechanical means for transferring said units figure to said product storage indicator, electromechanical means for temporarily storing said tens figure in said tens storage indicator, electromechanical tens adding means for adding to the units figure of each partial product the tens figure temporarily stored during the formation of the preceding product, and electromechanical means for adding to each total figure transmitted by said tens adding means the preceding figure stored by the product storage indicator in the same denomination.

3. A calculating machine comprising a multiplicand storage indicator, a multiplier storage indicator, a product storage indicator and a tens storage indicator, electric contact means selectively operable by said multiplicand and multiplier storage indicators, a distributor adapted to send an electric current successively into each denomination of the multiplier storage indicator, and, for each of said denominations of the multiplier storage indicator, into each denomination of the multiplicand storage indicator, a group of multiplying circuits adapted to be connected to said multiplicand and multiplier storage indicators and giving the units figure and the tens figure of each partial product, electromechanical means for transferring said units figure to said product storage indicator, electromechanical means for temporarily storing said tens figure in said tens storage indicator, a group of tens adding circuits which adds to the units figure of each partial product, the tens figure temporarily stored during the formation of the preceding product, said tens adding circuits comprising a group of wires which correspond respectively to the figures representing the units of the partial products of the multiplier figures by the multiplicand figures, a series of nine electromagnets, each of which is energized when the corresponding figure is entered in the tens storage indicator and the distributor sends current into the latter, and a series of nine sets of wires, each of which sets has a switch which is closed when the corresponding electromagnet of said series of nine electromagnets is energized, whereby the wire of the group corresponding to the figure representing the units of the partial product of the multiplier figure by the multiplicand figure is connected to that wire of a group of circuits which corresponds to the units figure of the sum of the figure supplied by the former group and of the figure supplied by the tens storage indicator, a group of transfer wires connected, by sets of wires provided with switches, when the sum of the figure supplied by the wire of the group corresponding to the figure representing the units of the partial product and of the figure supplied by the tens storage indicator is greater than 9, to a transfer conductor which places in the transfer position a reversing switch which will become operative in the course of the following operation, to increase by one unit the figure transmitted by the last mentioned group, and electromechanical means for adding to each total figure transmitted by said tens adding means, the preceding figure stored by the product storage indicator in the same denomination.

4. A calculating machine comprising a multiplicand storage indicator, a multiplier storage indicator, a product storage indicator and a tens storage indicator, electric contact means selectively operable by said multiplicand and multiplier storage indicators, a distributor adapted to send an electric current successively into each denomination of the multiplier storage indicator, and, for each of said denominations of the multiplier storage indicator, into each denomination of the multiplicand storage indicator, a group of multiplying circuits adapted to be connected to said multiplicand and multiplier storage indicators and giving the units figure and the tens figure of each partial product, electromechanical means for transferring said units figure to said product storage indicator, electromechanical means for temporarily storing said tens figure in said tens storage indicator, electromechanical means associated with said storage indicators for storing the transfers, a group of tens adding circuits which add to the units figure of each partial product, the tens figure temporarily stored during the formation of the preceding product, and

send an electric current successively into each denomination of the multiplier storage indicator, and, for each of said denominations of the multiplier storage indicator, into each denomination of the multiplicand storage indicator, a group of multiplying circuits adapted to be connected to said multiplicand and multiplier storage indicators and giving the units figure and the tens figure of each partial product, electromechanical means for transferring said units figure to said product storage indicator, electromechanical means for temporarily storing said tens figure in said tens storage indicator, a group of tens adding circuits which adds to the units figure of each partial product, the tens figure temporarily stored during the formation of the preceding product, said tens adding circuits comprising a group of wires which correspond respectively to the figures representing the units of the partial products of the multiplier figures by the multiplicand figures, a series of nine electromagnets, each of which is energized when the corresponding figure is entered in the tens storage indicator and the distributor sends current into the latter, and a series of nine sets of wires, each of which sets has a switch which is closed when the corresponding electromagnet of said series of nine electromagnets is energized, whereby the wire of the group corresponding to the figure representing the units of the partial product of the multiplier figure by the multiplicand figure is connected to that wire of a group of circuits which corresponds to the units figure of the sum of the figure supplied by the former group and of the figure supplied by the tens storage indicator, a group of transfer wires connected, by sets of wires provided with switches, when the sum of the figure supplied by the wire of the group corresponding to the figure representing the units of the partial product and of the figure supplied by the tens storage indicator is greater than 9, to a transfer conductor which places in the transfer position a reversing switch which will become operative in the course of the following operation, to increase by one unit the figure transmitted by the last mentioned group, and electromechanical means for adding to each total figure transmitted by said tens adding means, the preceding figure stored by the product storage indicator in the same denomination.

5. A calculating machine comprising a multiplicand storage indicator, a multiplier storage indicator, a product storage indicator and a tens storage indicator, electric contact means selectively operable by said multiplicand and multiplier storage indicators, a distributor adapted to send an electric current successively into each denomination of the multiplier storage indicator, and, for each of said denominations of the multiplier storage indicator, into each denomination of the multiplicand storage indicator, a group of multiplying circuits adapted to be connected to said multiplicand and multiplier storage indicators and giving the units figure and the tens figure of each partial product, electromechanical means for transferring said units figure to said product storage indicator, electromechanical means for temporarily storing said tens figure in said tens storage indicator, electromechanical means associated with said storage indicators for storing the transfers, a group of tens adding circuits which add to the units figure of each partial product, the tens figure temporarily stored during the formation of the preceding product, and

a group of adding circuits which add to each total figure transmitted by said group of tens adding circuits, the preceding figure stored by the product storage indicator in the same denomination, said group of adding circuits including a group of wires which corresponds to the units figure of the sum of the figure supplied by the wire of the group corresponding to the figure representing the units of the partial product of the multiplier figure by the multiplicand figure and of the figure supplied by the tens storage indicator, a series of ten electromagnets, each of which is energized when the corresponding figure is entered in the product storage indicator and the distributor sends current into the latter, and a series of ten sets of wires, each of which is provided with a switch which is closed when the corresponding electromagnet of said series of ten electromagnets is energized, whereby that wire of said group of wires which receives current is connected to that wire of a group of circuits which corresponds to the unit figure of the sum of the figure supplied by the said group of wires and of the figure transferred from the product storage indicator.

6. A calculating machine comprising a multiplicand storage indicator, a multiplier storage indicator, a product storage indicator and a tens storage indicator, electric contact means selectively operable by said multiplicand and multiplier storage indicators, a distributor adapted to send an electric current successively into each denomination of the multiplier storage indicator, and, for each of said denominations of the multiplier storage indicator, into each denomination of the multiplicand storage indicator, a group of multiplying circuits adapted to be connected to said multiplicand and multiplier storage indicators, and giving the units figure and the tens figure of each partial product, electrical means for transferring said units figure to said product storage indicator, electromechanical means for temporarily registering said tens figure in said tens storage indicator, a group of tens adding circuits which add to the units figure of each partial product, the tens figure temporarily stored during the formation of the preceding product, and a group of adding circuits which add to each total figure transmitted by said group of tens adding circuits, the preceding figure stored by the product storage indicator in the same denomination, said group of adding circuits including a series of ten electromagnets, each of which is energized when the corresponding figure is entered in the product storage indicator and the distributor sends current into the latter, said product storage indicator including two associated storing panels, operating alternately, for each figure of the multiplier storage indicator, one as a storing panel receiving the results from said group of adding circuits, the other as a transmitting panel controlling the energization of said series of ten electromagnets.

7. A calculating machine comprising a multiplicand storage indicator, a multiplier storage indicator, a product storage indicator and a tens storage indicator, an electromagnet adapted to disconnect said storage indicators, electric contact means selectively operable by said multiplicand and multiplier storage indicators, a distributor adapted to send an electric current successively into each denomination of the multiplier storage indicator, and, for each of said

denominations of the multiplier storage indicator, into each denomination of the multiplicand storage indicator, a group of multiplying circuits adapted to be connected to said multiplicand and multiplier storage indicators, and including a series of nine electromagnets, each of which is energized when the digit to which it corresponds is entered in the multiplier storage indicator and the distributor sends current into the corresponding order, said group of multiplying circuits giving the units figure and the tens figure of each partial product, electromechanical means for transferring said units figure to said product storage indicator, electromechanical means for temporarily storing said tens figure in said tens storage indicator, a series of nine electromagnets, each of which is energized when the corresponding figure is entered in the tens storage indicator and the distributor sends current into the latter, a series of ten electromagnets, each of which is energized when the corresponding figure is entered in the product storage indicator, said product storage indicator including two associated storing panels, operating alternately, for each figure of the multiplier storage indicator, one as a storing panel receiving the results from said group of adding circuits, the other as a transmitting panel controlling the energization of said series of ten electromagnets, said distributor controlling the selection operations performed, column by column, on the multiplier storage indicator, and for each column of the latter, the selection operations performed, column by column, on the multiplicand storage indicator, and also controlling the electromagnets selecting the denominations in the tens storage indicator and in the product storage indicator, the electromagnets controlling the reversal of the functions of said two storing panels, and the disconnecting electromagnet of said storage indicators and of the reversing transfer switches.

8. A calculating machine comprising a multiplicand storage indicator, a multiplier storage indicator, a product storage indicator and a tens storage indicator, electric contact means selectively operable by said multiplicand and multiplier storage indicators, a distributor adapted to send an electric current successively into each denomination of the multiplier storage indicator, and, for each of said denominations of the multiplier storage indicator, into each denomination of the multiplicand storage indicator, a group of multiplying circuits adapted to be connected to said multiplicand and multiplier storage indicators, and including a series of nine electromagnets, each of which is energized when the digit to which it corresponds is entered in the multiplier storage indicator and the distributor sends current into the corresponding order, said group of multiplying circuits giving the units figure and the tens figure of each partial product, electromechanical means for transferring said units figure to said product storage indicator, electromechanical means for temporarily storing said tens figure in said tens storage indicator, a series of nine electromagnets, each of which is energized when the corresponding figure is entered in the tens storage indicator and the distributor sends current into the latter, a series of ten electromagnets, each of which is energized when the corresponding figure is entered in the product storage indicator and the distributor sends current into the latter, ~~said~~ 75

product storage indicator including two associated storing panels, operating alternately, for each figure of the multiplier storage indicator, one as a storing panel receiving the results from 5 said group of adding circuits, the other as a transmitting panel controlling the energization of said series of ten electromagnets, said distributor controlling the selection operations performed, column by column, on the multiplier 10 storage indicator, and for each column of the latter, the selection operations performed, column by column, on the multiplicand storage indicator, and also controlling the electromagnets selecting the denominations in the tens storage 15 indicator and in the product storage indicator, the electromagnets controlling the reversal of the functions of said two storing panels, and the disconnecting electromagnet of said storage indicators and of the reversing transfer switches, 20 said storage indicators comprising panels of pins which have an electromagnet for each column and an electromagnet for each row, said electromagnet enabling any of said pins to be brought into the closed position, such pin thereby closing 25 the corresponding contact.

9. A calculating machine comprising a multiplicand storage indicator, a multiplier storage indicator, a product storage indicator and a tens storage indicator, electric contact means selectively operable by said multiplicand and multiplier storage indicators, a distributor adapted to send an electric current successively into each denomination of the multiplier storage indicator, and, for each of said denominations of the multiplier storage indicator, into each denomination 5 of the multiplicand storage indicator, said distributor comprising two spindles, cams mounted on both of said spindles, those on one being adapted to actuate the contacts for the selecting operations performed in the multiplier storage 15 indicator, and those on the other to actuate the contacts for the selecting operations performed in the multiplicand storage indicator, said two spindles rotating at relative speeds such that for a selecting operation performed in one de- 20 nomination of the multiplier storage indicator, a selecting operation is performed in all the denominations of the multiplicand storage indicator.
